UNITED STATES PATENT OFFICE.

FREDERICK W. HALL, OF CAMDEN, NEW JERSEY.

BOTTLE-SEALING DEVICE.

No. 857,619.

Specification of Letters Patent.

Patented June 25, 1907.

Application filed May 31, 1906. Serial No. 319,485.

To all whom it may concern:

Be it known that I, FREDERICK W. HALL, a citizen of the United States, residing at Camden, in the State of New Jersey, have 5 invented certain new and useful Improvements in Bottle-Sealing Devices, of which the following is a full, clear, and exact description, reference being had to the accompanying drawings, forming a part of this 10 specification.

My invention relates to that class of bottle sealing devices comprising a hard metal cap with continuous annular flange operating to maintain a contained compressible disk 15 or crown lining in sealing contact with the mouth of a bottle having a relatively projecting annular shoulder below the lip thereof. In such devices the bottle mouth closure is effected by external pressure applied 20 by a suitable tool on the crown of the cap, which forces the contained compressible disk or crown lining into sealing contact with the mouth of the bottle and also brings the flange 25 of the containing cap into a suitable position for applying to it a circumferential bending compression to effect a locking contact between it and the annular shoulder of the bottle, and thereby maintaining the compressible sealing disk under vertical pressure and 30 hence in sealing contact with the bottle mouth.

An early device of that class is shown and described in British Letters Patent No. 13062 dated October 13, 1886 to Pitchler, and my 35 invention about to be described is an improvement thereon having for its object to secure a locked relation of the cap with the bottle head without requiring any bending of the metal of the flange around the projecting annular shoulder of the bottle. This 40 is effected by my novel construction of the cap flange hereinafter described, providing thereby novel means of setting it in locked relation to the annular shoulder of the bottle, and whereby also it may be easily removed 45 when desired to open the bottle.

To these ends my invention consists of a hard metal sealing cap comprising a circular crown with an integral depending continuous 50 flange provided with an annular inturned open groove intermediate its length and an outwardly inclined annular rim below and extending from the lower wall of the open groove; also in the combination therewith 55 of a compressible sealing medium, which is preferably resilient under compression,

adapted to be contained within the cap and cover the mouth of the bottle, and a bottle having an annular shoulder below the lip thereof; said elements being so proportioned 60 and arranged that when initially assembled the central horizontal plane of the flange groove coincides with the central horizontal plane of the projecting annular bottle shoulder, and after said compressible sealing medium and bottle mouth are brought into sealed relation by pressure applied to the crown of the cap, the inwardly turned open groove of the flange will be thereby brought into a slightly lower horizontal plane and 65 below the central plane of said shoulder, and is then sprung into locked relation therewith, by radially applied pressure on the extreme lower edge of the outwardly-inclined projecting rim extending downward from the 70 lower wall of the inturned open groove, and which operates to bring said rim into substantial vertical alignment with that portion 75 of the flange above the groove therein.

In the drawings illustrating my invention:—Figure 1 is a vertical section of the bottle element and the disk element, each of a character adapted to be used with my caps. Fig. 2 is an elevation thereof, in perspective. Fig. 3 is a modification thereof showing the 85 cap lined with paper. Fig. 4 is a vertical section of the cap, disk and bottle elements in initial position. Fig. 5 is the same when pressure has been applied to the crown of the cap, compressing the disk vertically and effecting a sealing relation between it and the bottle mouth, and bringing the groove of the flange into a horizontal plane below that of the largest diameter of the shoulder of the bottle; and Fig. 6 is an elevation in perspective, partly in section, of the same elements, brought from the position shown in Fig. 5 to combined or finished position, wherein radially applied pressure on the extreme edge 90 of the projecting rim below the inturned open 95 groove has sprung the latter under the annular shoulder of the bottle and thus effected a locked relation therewith.

The cap element of my device is made of hard metal, such as roofer's tin, of which 105 such caps are commonly made, and it may be most cheaply and satisfactorily produced by suitable dies in a stamping-up press. The cap consists of a crown portion *a* with integral depending annular flange *b*, which is to 110 be continuous and without slits. Somewhat below a medial line in the length of the

flange (depending upon the distance between the lip *e* of the bottle and its shoulder *h* at its greatest circumference) the flange is formed with an annular narrow groove *c*, which is to be constructed as an open groove, and with its wall facing inwardly, leaving a narrow portion *d* of the flange below and extending from the lower wall of this groove or bead *c*, which is to be slightly expanded outwardly so as to 10 form a narrow edge rim slightly inclined outwardly from the vertical.

The action of the forming-dies in compressing the metal to form the inwardly-facing open groove *c*, in conjunction with the co-acting dies which slightly expand the edge 15 rim *d* below the lower wall of the groove, in giving such rim an outward incline, results in a construction in which the said expanded rim may be afterward readily compressed, by 20 very slight radial pressure on its extreme annular edge, while it is obvious that under such compression, the force applied to the edge of the rim *d* will extend to the lower wall of the open and inwardly-facing groove 25 and, without bending the metal at all, at any point where it touches or may touch the glass, will operate to spring the annular edge of the groove under the shoulder of the bottle, because the consequent effect of radially compressing the said narrow flange rim *d* into the 30 same vertical plane with the upper cylindrical portion of the flange above the groove, is to slightly contract the circumference of the annular edge of the inturned open 35 groove, and this without in any sense binding the metal of any part of the flange which can or may contact with the glass in effecting such locking relation. It is quite true that such reduction of circumference of the inner 40 edge of the groove is very small, in fact is merely line-like in extent, but it is quite sufficient to lock the cap securely on the bottle head, for if said inner wall of the groove is reduced in circumference, even to the slightest 45 appreciable extent, below the greatest circumference of the bottle shoulder, it will be impossible to remove it from the bottle without again expanding the rim *d* into the initial form and circumference, which it had when 50 applied to the bottle (as shown in Figs. 4 and 5).

The bottle element of my device is provided with an annular shoulder *h* below the mouth of the bottle, and a lip *e* at some slight 55 distance above the projecting annular edge of the shoulder *h*, the distance between them being sufficient, relatively to the length of the cap flange and the thickness of the sealing disk, that when initially applied as shown 60 in Fig. 4, the central plane of the groove will be in about the same horizontal plane with the central plane of the annular shoulder of the bottle. In forming the lip *e* and shoulder *h*, I prefer the form shown in the drawings, wherein the lip *e* is somewhat thin and 65

is therefore better adapted to enter the disk, as seen in Fig. 5, and wherein the annular edge *h'* of the bottle shoulder *h* is shown as rather sharply defined by sloping the portion *m* of the bottle head, which is between the 70 extreme upper edge of the lip *e* and the circumferentially largest part of the shoulder *h*.

The disk element *n* is preferably of cork, or some other sealing medium which is distinctly and appreciably compressible, and I 75 prefer a cork disk of about an eighth of an inch in thickness, because under vertical compression it will be resilient, which not only helps sealing contact but tends to exert a continuing upward pull to maintain the 80 parts in said combined and locked relation. As cork however is not always of good quality and is apt to dry, causing leakage, the cap may be lined with paper as shown at *s*, Fig. 3, and thus used either with or without 85 the cork disk, but preferably with it. With such paper lining a hermetic seal may be made, as the contact of the lined groove of the flange against the smooth underface of the shoulder of the bottle will at all times 90 prevent the access of air to the bottle or to the interior of the cap below the lip of the bottle.

In sealing the device upon the bottle, the elements are assembled as shown in Fig. 4; 95 pressure upon the crown of the cap will compress the disk and effect a sealed relation between it and the bottle mouth, such vertical pressure also lowering the flange into a horizontal plane lower by the depth to which the 100 lip of the bottle has entered the cork disk, as shown in Fig. 5. If the parts are properly made and properly proportioned, the central plane of the groove will coincide with the central plane of the annular projecting shoulder 105 of the bottle, as shown in Fig. 4; but after compression of the disk the plane of the groove will be slightly below the largest circumference of the bottle shoulder, as shown in Fig. 5, and ready to be sprung into locked 110 relation thereto, which is as shown in Fig. 6.

An additional and distinct advantage of forming the open inwardly-facing groove with an outwardly-inclined narrow rim beneath it is, that when such locking contact is 115 effected, this rim edge will stand off somewhat from the surface of the bottle, due entirely to the inwardly-inclined under surface of the bottle shoulder, as seen in Fig. 6, affording a most ready means of inserting a 120 knife or other opener, and by expanding the rim edge restore the parts to initial condition sufficiently at least to readily remove the cap from the bottle.

In the before-mentioned bottle sealing devices of this class great power was required to bend the flange of the cap, large and expensive cap-setting machines being used for the purpose. With my device the simplest kind of setting machine, requiring very little 125 130

labor to operate, and of trifling cost, may be used, for example a cylindrical plunger operating within a cylindrical sleeve, with suitable means supporting and actuating the 5 plunger, the head of the plunger being the size of the crown of the cap, acting first thereon to compresss the disk and bring the cap into a relatively lower horizontal plane, followed by a descent of the cylindrical sleeve, 10 the inner diameter of which is slightly larger than the outer diameter of the crown cap, hence striking in its descent, the extreme edge of the inclined rim of the flange below the groove, and bringing both into the position shown in Fig. 6 wherein the inner annular edge of the groove has been slightly contracted in circumference and thereby sprung beneath the bottle shoulder, and said rim of the flange though vertical, stands off from 15 20 the under inclined surface of the bottle shoulder.

Having thus described my invention, I claim as new and desire to secure by Letters Patent:—

25 1. A hard-metal sealing cap having a disk-shaped crown with an integral and continuous annular flange which is provided intermediate its length with an inturned open groove and an outwardly inclined rim edge 30 35 below and proceeding from the lower wall of said groove.

2. In a sealing device, the combination 40 with a bottle having a lip and below it a projecting annular shoulder, a compressible sealing medium under sealing pressure on the bottle lip, and means to maintain said elements in sealed relation, consisting of a hard metal sealing cap having a continuous annular flange provided with an inturned open groove intermediate its length adapted initially to pass over the bottle shoulder, and

below it a rim edge initially inclined outwardly, whereby when radial pressure is applied to said inclined rim edge to bring it into substantially the same vertical plane with 45 the portion of the flange above the groove, the inner annular edge of the groove will be slightly contracted circumferentially and sprung into locked contact with the underface of the bottle shoulder. 50

3. A sealing device comprising a bottle having a head provided with a projecting annular shoulder between its lip and neck, a compressible sealing medium, and a hard metal sealing cap having a continuous flange 55 provided intermediate its length with an open and inturned annular groove and a depending rim proceeding from the lower wall thereof, said groove being brought into locked relation to the annular shoulder of the 60 bottle.

4. A sealing device consisting of the combination with a bottle having a projecting annular locking shoulder between its lip and neck, a compressible sealing disk under sealing pressure on the lip of the bottle, and a paper-lined hard metal sealing cap having a continuous annular flange provided intermediate its length with an open inturned annular groove and an annular rim edge proceeding 70 from the lower wall thereof, and which is brought into a substantially vertical plane when the groove of the cap is in locked relation to the bottle shoulder.

In testimony whereof, I have hereunto affixed my signature this twenty sixth day of April A. D. 1906. 75

FREDERICK W. HALL.
